(57) **CLAIM**

The ornamental design for a pan, as shown and described.

DESCRIPTION

FIG. 1 is a top, front, right-side perspective view of a pan showing my new design;

FIG. 2 is a bottom, back, left-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is a cross-section view thereof taken along the disclaimed line 9-9 shown in FIG. 3; and,

FIG. 10 is a cross-section view thereof taken along the disclaimed line 10-10 shown in FIG. 5.

The dot-dot-dash lines indicate the locations of the cross section views and form no part of the claimed design.
